(57) **CLAIM**

The ornamental design for a housing for electronic communication devices, as shown and described.

DESCRIPTION

FIG. 1 shows a top view of a housing for electronic communication devices;

FIG. 2 shows a side view of the housing for electronic communication devices;

FIG. 3 shows a further side view of the housing for electronic communication devices;

FIG. 4 shows a front view of the housing for electronic communication devices;

FIG. 5 shows a rear view of the housing for electronic communication devices;

FIG. 6 shows a bottom view of the housing for electronic communication devices;

FIG. 7 shows a perspective view of the housing for electronic communication devices; and,

FIG. 8 shows a perspective view of the housing for electronic communication devices.

The broken lines consisting of unevenly sized dashes define the boundary of the claim, which extends to the boundary but does not include the boundary, while the remaining broken lines in FIGS. 1 and 7 depict parts of the housing for electronic communication devices that form no part of the claimed design. All broken lines form no part of the claim.
